ROLLING MILL

Filed April 27, 1922

Inventor:
J. W. Shepherdson
By G. W. Kennedy, Jr.
Attorney.

UNITED STATES PATENT OFFICE.

JOHN W. SHEPERDSON, OF WORCESTER, MASSACHUSETTS, ASSIGNOR TO MORGAN CONSTRUCTION COMPANY, OF WORCESTER, MASSACHUSETTS, A CORPORATION OF MASSACHUSETTS.

ROLLING MILL.

Application filed April 27, 1922. Serial No. 557,017.

To all whom it may concern:

Be it known that I, JOHN W. SHEPERDSON, a citizen of the United States, residing at Worcester, in the county of Worcester and 5 Commonwealth of Massachusetts, have invented a new and useful Improvement in a Rolling Mill, of which the following, together with the accompanying drawing, is a specification.

10 The present invention relates generally to rolling mills. The invention resides in a novel combination and arrangement of roll trains and auxiliary equipment, which adapts itself not only to the rolling and handling 15 of a diversified product of ordinary steel billets, sheet bar and the like, but also to the convenient production, when desired, of various shapes made of special alloy steels.

15 The various features and advantages of 20 the invention are fully set forth in the following description, reference being had to the accompanying drawing, the single figure of which is a diagrammatic plan view of rolling mill apparatus combined and arranged in accordance with the invention.

25 Referring to said drawing, 1 represents a 30 blooming mill of ordinary construction for the reduction of ingots taken from soaking pits, not shown. By any suitable conveying 35 means, indicated diagrammatically at 2, the product of the blooming mill 1 is carried to a billet and slab mill 3, the rolls of which, preferably, provide a plurality of differently-shaped rows of passes, to give 40 such variety as may be desired in the cross-section of the reduced material emerging therefrom.

45 The reduced product of roll train 3, consisting of billets, slabs and the like, is received upon a conveying mechanism 4 of any suitable construction and is carried longitudinally forward in the direction of a sheet bar mill 5, constituted by a roll train 50 which provides one or more stands of edging rolls 6, 6. As herein shown, the conveying mechanism 4 does not deliver the product of roll train 3 directly to the roll train 5, but on the contrary, said roll train 5 receives said product from a suitable longitudinal conveying mechanism 7, which is 55 offset from the line of delivery of conveying mechanism 4. Interposed between the conveying mechanisms 4 and 7 is a suitable broadside transfer mechanism 8, by the operation of which the stock may be moved,

as rapidly or as slowly as desired, across the intervening space; the transfer mechanism 8 thus constitutes, in effect, a delay table, the function of which is to permit as much or as little time to elapse, as may be desired, 60 for the cooling of such of the products of the roll train 3 as may need a lower temperature for their further reduction by rolling.

65 For the disposition of the other products of the mills 1 and 3, provision is made for the broadside transfer of the same to a suitable longitudinal conveying mechanism 9, which delivers in one direction to a roll train 10 and in the other direction either 70 to the cooling beds 11, 11, or to the cooling cars or trucks 12, or to both, as may be desired. Interposed between the conveying mechanisms 4 and 9 is a suitable broadside 75 transfer mechanism 13, similar in its capabilities to the transfer mechanism 8 and operating, when desired, as a delay table on which to accomplish any requisite cooling 80 of the material. Such material as is delivered to the mill 10 by the conveying mechanism 9, after undergoing reduction in the successive passes of the roll train, is disposed of in the usual fashion by a shear 14 and cooling beds 15; such mechanism, 85 as well as the corresponding shear 16 and cooling beds 17 which are provided in connection with the sheet bar mill 5, form no 90 part of the present invention and hence need not be described in detail.

95 The above described arrangement of apparatus lends itself particularly to the convenient and expeditious treatment of any of the desired alloy steel products of the mills 1 and 3, that require the removal of surface imperfections before any further rolling is done. Such material, as delivered by the transfer mechanism 13 to the conveying mechanism 9, is carried rearwardly by said 100 conveying mechanism and acted upon by a shear 18, the pieces, being then disposed for cooling either on the cooling beds 11 or on the cars 12. In either case, such material is eventually delivered in convenient location for the operation of chipping, to remove the surface imperfections, or for any other operation required, 105 before further rolling action thereon. In order to heat such material, to prepare it for further rolling, furnaces 19 are provided, and so arranged, with relation to the con- 110

veying mechanism 9, that the billets discharged from said furnaces are received directly on said conveying mechanism, in condition to be forwarded, without delay, to the roll train 10. The latter, if desired, may have as part of its equipment, one or more stands of edging rolls 20, 20, corresponding to the stands of rolls 6, 6 or sheet bar mill 5, and by the use of which sheet bar may be rolled. The apparatus further provides an additional broadside transfer mechanism 21, which connects the conveying mechanism 9 with the conveying mechanism 2, in advance of the reducing roll train 3. It is thus possible to procure, when desired, the passage of pieces of large section directly from the blooming mill 1 to the cooling devices 11 or 12.

I claim:

20. 1. Apparatus of the class described, comprising, in combination, longitudinal conveying mechanism for the product of a billet and slab mill, two independent reducing roll trains adapted, selectively, to receive said product, and a delay table interposed between said conveying mechanism and both of said roll trains.
30. 2. Apparatus of the class described, comprising, in combination, longitudinal conveying means for the product of a billet and slab mill, two independent reducing roll trains adapted, selectively, to receive said product, the center lines of each of said roll trains being offset from said conveying means, and a broadside transfer, constituting a delay table for cooling the product, interposed between said conveying means and each of said roll trains.
40. 3. Apparatus of the class described, comprising, in combination, a reducing roll

train, conveying means normally operable to deliver material directly thereto, and means served in common by said conveying means for obtaining the cooling, storing, chipping, and reheating of said material, 45 prior to its delivery to said roll train.

4. In apparatus of the class described, comprising, in combination, a broadside transfer mechanism for the product of a billet and slab mill, a longitudinal conveying mechanism adapted to receive said product from said transfer mechanism, and means, selectively operable, either to procure the further reduction of said product as received on said conveying mechanism, or to procure 50 intermediate surface treatment and reheating of the same before resumption of rolling.

5. In apparatus of the class described, a reducing roll train, a longitudinal conveying mechanism associated therewith and adapted 60 to deliver thereto, means for delivering material broadside to said longitudinal conveying mechanism, and means for procuring, when desired, the intermediate treatment of said delivered material, prior to its passage 65 to said reducing roll train.

6. In apparatus of the class described, a reducing roll train, a longitudinal conveying mechanism adapted to deliver material thereto, a heating device adapted to deliver 70 material to said longitudinal conveying mechanism, and means for delivering material broadside to said longitudinal conveying mechanism intermediate said roll train and said heating device, whereby to permit 75 reheating of said material prior to its reduction by said roll train.

Dated April 17, 1922.

JOHN W. SHEPERDSON.
